TUMBLER

William Lloyd Cone, Dallas, Tex., assignor to
Plastics Manufacturing Company, a corpora-
tion of Texas

Application August 23, 1949, Serial No. 4,668

Term of patent 3½ years

(Cl. D36—8)

To all whom it may concern:

Be it known that I, William Lloyd Cone, a citizen of the United States, residing at Dallas, in the county of Dallas and State of Texas, have invented a new, original, and ornamental Design for a Tumbler, of which the following is a specification, reference being had to the accompanying drawings, forming part thereof.

In the drawings:

Figure 1 is a front elevation of a tumbler embodying my new design;

Figure 2 is a side elevation partly in vertical section;

Figure 3 is a section taken along the line 3—3 of Figure 2.

I claim:

The ornamental design for a tumbler, as shown.

WILLIAM LLOYD CONE.
